UNITED STATES PATENT OFFICE.

JACOB W. WILSON, OF SUMMERFORD, OHIO.

GRAIN-BINDER.

SPECIFICATION forming part of Letters Patent No. 250,620, dated December 6, 1881.

Application filed June 15, 1881. (No model.)

To all whom it may concern:

Be it known that I, JACOB W. WILSON, of Summerford, Madison county, Ohio, have invented certain new and useful Improvements in Harvester-Binders; and I do hereby declare the following to a full, clear, and exact description of the same, reference being had to the accompanying drawings, forming part of this specification, in which—

10 Figure 1 is a top-plan view of my machine; Fig. 2, a rear elevation; Fig. 3, a side elevation; Fig. 4, a top-plan view of the platform carrying the raking and binding mechanism, with the binding-table removed. Fig. 5 is a 15 view showing the under side of the binding-table and parts attached thereto; Fig. 6, a sectional view taken on the line 11, Fig. 5. Fig. 7 is a detailed view of parts of the looping and tying mechanism. Fig. 8 is a sectional view 20 taken longitudinally through the platform. Fig. 9 is a perspective view of the raking-frame; Fig. 10, a bottom-plan view of the frame $D^{6x} D^{6x}$, carrying parts of the binding mechanism; Fig. 11, a detail view, showing the rake-frame 25 and the cam for raising the catch or pawl to release the rake-head and permit the rake-teeth to fall down. Fig. 12 is a view of part of the rake-frame. Fig. 13 shows the end of the rake-head and the devices for holding it when the 30 teeth are elevated, together with the cam for releasing it; Fig. 14, Sheet 3, a view of the binding-arm and its clamps. Fig. 15 is a perspective view of the bar T detached.

My invention has for its object to provide a 35 harvester-binder in which the cut grain that falls upon the grain-platform shall be carried directly to a binding mechanism located at one end of the platform by means of a raking mechanism arranged on the platform itself; and it 40 consists in a machine embodying certain novelties of construction and combinations of parts, whereby my said object is obtained, which machine I will now proceed to describe.

In the drawings, A represents the main frame 45 of the machine, mounted upon suitable wheels, B B, and not differing materially from the frame of an ordinary mowing or reaping machine, except that it is formed with or has bolted to it a rearwardly-projecting bar, C, to which 50 is adapted to be suspended by means of a bar, D', a platform, D, containing the cutting, raking,

ing, and binding mechanism of the machine, the said platform being further supported by a drag-bar, D², at its front edge, and a grain-wheel, D³, at its outer end, as shown.

E is a reel mounted upon a standard extending upward from the drag-bar, and receiving motion through an endless chain passing over a sprocket-wheel on the end of its shaft, and also around a similar wheel fixed to the revolving main axle or to the hub of one of the wheels B, in the usual manner.

The platform D is preferably constructed of longitudinal front and rear bars or timbers, D⁴ D⁴, end cross-bars, D⁵ D⁶, an intermediate frame, D^{6x}, carrying a part of the knotting mechanism, and a plate or table, D⁷, carrying on its under side other parts of the knotting mechanism, and constituting also the table onto which the sheaves are gathered and held while being bound. The under side of the platform, beneath the binding mechanism, is covered with a bottom, D⁸, while its upper side, where the cut grain falls, is provided with a longitudinally-slotted top extending from the outer 75 end of the platform to the binders' table, as shown.

The front and rear timbers, D⁴ D⁴, are provided upon their inner faces with longitudinal grooves or guides d d back and forth, in which is adapted to slide a rake-frame, F, carrying a rake-head, F', armed with teeth f, which are adapted to project up through the slots in the top of the platform. The rake-frame is connected to an endless chain, F², which passes 85 around a sprocket-wheel, F³, at the outer end of the platform and around another sprocket-wheel, F⁴, mounted upon a vertical shaft, F⁵, supported in a bracket, F⁶, at the inner end of the platform. The shaft F⁵ is provided with 90 a pinion, F⁷, with which engages the rack-toothed end of a pitman, F⁸, operated from a crank, F⁹, on the end of the main axle of the machine. The rack-teeth of the pitman are kept at all times engaged with the pinion by 95 means of a guide, F¹⁰, that plays through an opening in an offset, F¹¹, of the bracket F⁶, and which is joined at both ends to the pitman, as shown. The connection of the pitman to the wrist of the crank is not permanent, but the 100 pitman is provided with a slot, F¹², which enables it to be engaged with or disengaged

from the wrist, as desired, by the co-operation of an arm, G, projecting from a rock-shaft, G', and kept under the control of the driver of the machine from his seat by means of a foot-lever, 5 G². When the pitman is in engagement with the crank-wrist the vibration of the latter causes the pitman to vibrate back and forth and its rack-toothed end to rotate the pinion and its shaft first in one direction and then in 10 the opposite direction, thereby imparting to the endless chain a reciprocating motion and causing the rake-frame and its rake to advance toward and recede from the binding apparatus. To arrest the operation of the rake it is only 15 necessary for the driver to press upon the foot-lever G², and elevate the arm G into the path of a lateral projection, g, on the end of the pitman, so that when the crank brings the pitman around the said arm will strike the projection and unship the pitman from the wrist, thus breaking the connection. The rake head 20 F' has its bearings in the forward end of the rake-frame, and its extremities, projecting into the grooves d, form the supports and guides 25 for that end of the frame.

When the rake-frame starts to move forward toward the binding mechanism a cam or projection, f', near one end of the rake-head, strikes the upturned end of a stationary spring, 30 f², and causes the rake-head to be rotated until its teeth f stand up vertically through the slots in the platform, in which position they are locked from further movement in either direction by the engagement of a spring-catch, 35 f³, mounted on the rake-frame with a notch in an enlargement, f⁴, at the opposite end of the rake-head. Continuing to advance, the rake-teeth gather the cut grain and sweep it up to and onto the binding-table into position to be 40 compressed and bound into a sheaf. Having thus delivered the grain to the binding-table, the further movement of the rake-frame causes the spring-catch f³ to be lifted from engagement with the notch in the enlargement f⁴ by 45 means of a cam, f⁵, on the side of the bar or front timber, D⁴, thereby releasing the head and permitting the teeth, as they strike the intermediate cross-frame, D⁶X, to be thrown down into horizontal position, where they remain 50 until the rake-frame is reciprocated back to its first position or starting-point.

Extending upward from the front and rear timbers of the platform, at opposite ends of the binding-table, are two standards, H H, and at 55 the upper ends of these standards is mounted a cross-shaft, H', carrying at or near its middle the binding-arm H². A fixed curved arm, H³, rises from the rear side of the binding-table, a little to one side of the plane in which the binding-arm moves, and to an extension or offset of the said fixed arm H³ is articulated a movable compressor-arm, H⁴, (see Fig. 8,) having a laterally-projecting pin or stud, h, which is adapted to engage with a slot in a short arm, h', 60 fixed to the shaft H', and against which the arm h² of a spring, h³, coiled about the shaft H', is

also adapted at certain times to bear. A yielding spring-arm, h⁴, is attached to the arm H³, as shown.

Secured to the end of the shaft H', at the rear side of the machine, is a crank, h⁵, and connected to the wrist of this crank is a bar, h⁶, which in turn is connected to the short arm of an angular bar, h⁷, pivoted to the platform at h⁸, and having an offset, h⁹, at its outer end, and a cam-slot, h¹⁰, extending nearly its entire length. h¹¹ is a pawl-arm, pivoted at h¹², and having a notch or shoulder, h¹³, which at certain times is adapted to engage with the offset h⁹, and having, also, an extended weighted end, which, 75 when the notch is engaged with the offset, extends over the bar h⁷ and across the slot therein.

Arranged at the rear side of the platform, and connected to the sliding-rake frame in any 80 suitable manner, is a bar, i, the same extending along the platform some distance, and having at its forward end a laterally-projecting pin, i', as shown.

At the time when the rake advances to sweep 90 the grain onto the binding-table the binding-arm is in an elevated position and the slotted bar h⁷ is down, so that the weighted pawl engages with its offset and extends across its slot. The movable compressor-arm is also ele- 95 vated, its lateral stud or pin h being held within the slot in the short arm h'. Just before the rake-teeth begin to fall down into horizontal position after delivering the grain onto the binding-table, the pin i' on the bar i enters the 100 slot in the inclined portion of the bar h⁷, strikes the end of the pawl-arm projecting across said slot, thereby disengaging the pawl from the offset, and, traveling along in the inclined portion of the slot, causes the bar to be elevated, 105 and through the connecting-bar h⁶ and crank h⁵ causes the shaft H' to be rotated. Soon after this shaft begins to rotate, and while the binding-arm is sweeping down, the pin h becomes disengaged from the slot in the arm h', 110 and the end of the coiled spring h³ strikes the said pin and causes the compressor-arm H⁴ to grasp the collected grain, form it into a bundle, and hold it with yielding pressure against the spring-arm h⁴, after which the binding-arm 115 passes the cord around it, as will be presently explained. The force with which the spring h³ bears upon the compressor-arm H⁴ may be regulated by adjusting the sleeve or ring i', to which the inner end of said spring is connect- 120 ed, and securing it by means of a set-screw, i³.

The knotting mechanism consists, mainly, of a longitudinally-sliding but non-rotating tube, K, around which the cord is wound to form the loop; a rotating outer cylinder or tube, 125 L, carrying a pair of spring jaws or nippers, l l', which grasp and hold the end of the cord while it is being looped about the inner tube, and a central longitudinally-sliding hook-bar, M, and co-operating bar N, which securely 130 grasp the end of the cord lying across the formed loop and pull it through the loop and within

the inner tube, so as to complete the knot and draw it tight.

The outer rotary cylinder or tube, L, is preferably mounted in hangers or bearings depending from the under side of the binding-table, and has a pinion, l^3 , upon its outer end, with which engages the teeth of a vibratory rack-bar or toothed segment, O. On the forward end of said tube L the jaws or nippers l^1 are mounted. These jaws are preferably of spring metal and of sufficient rigidity to hold securely a strand or strands of cord forced between them, and the outer jaw, l^1 , has a stud or projection, l^4 , on its inner side, which passes through a perforation in the inner jaw, l^5 , and projects inward a short distance beyond the latter.

The inner non-rotating tube, K, extends longitudinally through the outer tube, L, and has secured to its rear end an arm, k, while on its front end it is provided with a radial projection, k^2 , which at certain stages of the tying operation is adapted to engage with the stud l^4 on the clamping-jaw l^1 , to open said jaw and permit the entrance of the cord between the two jaws. The said projection k^2 is also adapted to enter a longitudinal slot in the outer tube, L, when the latter is stationary and the inner tube is moved longitudinally, as will be presently explained.

The central retracting hook-bar, M, extends through the inner tube, K, and is curved around at its rear end and bifurcated to receive the lower end of the arm k of the tube K. It also has a pin, m, which engages with an arm, Q, pivoted at q and having a spring on its pivot operating to press the arm inward.

The bar N, which co-operates with the hook-bar M to clamp and draw inward the end of the cord, lies alongside the bar M in the tube K, and has a downwardly-projecting arm, n, at its rear end, against which a spring, n^2 , bears, so as to exert a forward pressure upon the bar.

The toothed vibratory rack-bar or segment O, which rotates the pinion of the tube L, is articulated to an arm, o, mounted upon a post or stud, o' , and to the lower end of this stud o' is secured a bell-crank lever, o^2 , one arm of which is slotted at o^{12} , and has an extension, o^3 , and the other arm of which is provided with a downwardly-projecting pin, o^4 . A vibratory motion is imparted to the bell-crank by means of a projection, o^5 , on the reciprocating rake-frame engaging with the slotted arm of said lever, and by an arm, o^6 , projecting from said rake-frame and co-operating with the downwardly-projecting pin o^4 on the bell-crank lever. Two projections, o^7 and o^8 , are formed upon the front side of the rack-bar, one of which, o^7 , operates to throw into action a pivoted cutting-knife P, when the rack-bar is vibrated in one direction, and the other of which, o^8 , serves to throw said knife out of action when the rack-bar is vibrated in the opposite direction.

The binding-arm, at its outer end, is provided with a cord-clamping device, R, consisting, preferably, of two thin metal fingers, r^1 ,

held closed together by their own elasticity, and flared a little at their outer ends to insure the entrance of the cord between them. Said arm is further provided with a curved arm, r^1 , which, as the arm descends, bears upon the top of the binding-table, and carries into a slot in the table the binding-cord. It is also provided at its end with a lateral projection, r^2 , which engages with a locking-catch, r^3 , below the binding-table when the binding-arm is down. Said catch is hinged at one end, and is normally held down by means of a spring, r^4 , but is adapted to be raised automatically by the engagement of a downward projection, r^6 , at its end with an arm, r^7 , located on the reciprocating rake-frame F.

S represents the spool or bobbin containing the binding-cord. It is held between bearings s^1 and s^2 , the former of which is rigid, while the latter is mounted upon a spring, s^3 , and is capable of being adjusted by means of a set-screw, s^4 , so as to bear with more or less pressure upon the ends of the spool, and thus regulate the tension. From the spool the cord passes through a perforation, s^5 , in a plate of the intermediate frame, and thence to the clamps on the binding-arm.

T, Figs. 4 and 15, is a centrally-pivoted lever, carrying at its rear end a wedge-shaped projection, t, which is adapted at certain intervals to rise and spread apart the clamps on the binding-arm, so as to admit the second strand of cord more readily. The front end of said lever is bent downward, and is provided with a lateral projection, t^1 , which is adapted to engage with an incline or cam, t^2 , on the reciprocating rake-frame when the latter moves toward the binding-table, for the purpose of throwing the rear end of the lever and its wedge-shaped projection upward. A spring, t^3 , beneath the forward end of the lever, keeps the rear end normally depressed.

Mounted upon a laterally-projecting stud on the top of the rear standard H is a bundle ejector or kicker, U, shaped somewhat like a pitchfork, and kept normally elevated by the action of a spring, u. A spur, u^1 , is formed upon or secured to the base of the crank h^5 , and co-operates with a projection, u^2 , on the ejector, to cause the latter to sweep toward the rear of the machine and carry off the sheaf or bound bundle from the binding-table.

From the foregoing detailed description the operation of the machine will be readily understood. When the machine starts to operate the binding-arm stands in an elevated position with the end of the cord held in its clamping device, while the rake-frame is at the outer end of the platform. As the machine advances the rake-frame is reciprocated toward the binding-table by the mechanism before described, and the elevated rake-teeth sweep the cut grain up to and onto the binding-table against the spring-arm h^4 . Just before the rake-teeth descend to a horizontal position, the laterally-projecting pin i^1 of the bar i enters the slot of

the pivoted bar h^7 , releases the pawl-arm from the offset, and, through the medium of the bar h^7 , connecting-bar h^6 , crank h^5 and shaft H' , causes the movable compressor-arm and 5 the binding-arm to one after the other descend, the former compressing the grain into a compact bundle, and the latter passing the cord around the same, the curved arm r' carrying the cord into the slot v in the binding-table, where 10 the first strand of cord already is. As the end of the binding-arm passes down under the binding-table the projection r^7 on the rake-frame raises the spring locking-catch r^3 , and permits the lateral projection r^2 on the binding-arm to 15 pass thereunder and be locked, thus securely holding the binding-arm. The clamps on the binding arm have meanwhile caught the second strand of cord between them, and both strands have been carried in between the spring 20 jaws or nippers l l' of the knotting mechanism, which are held open by the engagement of the stud l^4 of the jaw l , with the radial projection k^2 on the inner tube, K . Immediately after the binding-arm has been secured by the locking- 25 catch, as aforesaid, or simultaneously with its being so secured, the cam t^2 on the rake-frame operates the lever T , so as to cause its wedge-shaped projection t to rise and open or spread apart the clamps of the binding-arm, to enable 30 them to take a firm hold upon the second strand of cord, after which the wedge-shaped projection o^5 on the rake-frame strikes the slotted arm of the bell-crank lever o^2 , and, through the medium of stud o^4 and arm o , causes the 35 rack-bar or toothed segment O to rotate the pinion P and the tube L , to which it is secured. As the tube L begins to rotate, its clamps or nippers l l' close tightly and hold the two strands of cord, and soon thereafter the projection o^7 40 on the rack-bar strikes the pivoted knife P , and causes it to sever the strands of cord close to the binding-arm clamps. The cylinder or tube L revolves about one and one-half time around, its clamps l l' holding securely the ends of the 45 cord meanwhile. During its first revolution it carries the cord completely around the end of the inner tube, K ; but when this is accomplished the stud o^5 on the rake-frame strikes the end y' of a spring-detent, Y , located on the 50 under side of the frame, and disengages said 55 detent from the downwardly-projecting arm k of the tube K , after which a cam, v' , on the back of the rack-bar O strikes the said arm k , and pushes the tube K a little backward longitudinally, so that on the next half-revolution the cord 60 will not be wound about the tube K , but will cross itself and be drawn over the end of said tube and behind the exposed hook of the hook-bar M . The continued movement of the rake-frame causes it next to strike at the point w the bifurcated end of the retracting hook-bar M and force said bar backward, its hook end pulling the ends of the cord completely within the tube K and against the forward end of the 65 co-operating bar N , the spring n' at the rear of the latter operating to hold said cord ends

securely and positively. A projection, w' , on the rake-frame then strikes and moves backward the spring-arm Q , and the latter then, by its connection with the pin on the end of bar M , forces still farther backward both the tube K and the bars M and N , the radial projection on the said tube sliding into the longitudinal slot in the end of tube L . As the tube K thus moves backward the loop of cord around 70 its end is pushed off by the stationary outer tube, L , after which the bars M and N , still holding securely the ends of the cord, pull the knot tight, thus completing the operation. Upon the movement of the rake back to its first 75 position the bars M and N release the ends of the cord and reset the binding mechanism, as will be readily understood. During such resetting movement, however, the kicker or ejector U is operated, and catching the bound bundle 80 with its teeth discharges it endwise from the machine.

The raking mechanism is pref rably so constructed and geared as to cause it to gather the grain and set in motion the binding mechanism every twelve or fifteen feet as the machine advances; but should the crop be light, the driver, by operating the foot-lever and disconnecting the slotted pitman from the driving crank, can cause said mechanism to operate 90 less frequently, or keep it out of operation altogether as long as desired.

It will be observed that in this machine the binding mechanism is operated entirely and directly by the raking mechanism, and that the 100 latter is not set in motion until the proper amount of cut grain has accumulated on the platform. This I regard an important feature, as by it the bundles or sheaves are kept of uniform size and more satisfactory work is performed.

The main frame of the machine is so constructed that the platform D can be detached, when desired, and the proper parts of an ordinary mower or reaper be attached in its place. 110 This is an economy to the farmer, as it renders it unnecessary for him to have but one main frame and driving mechanism to operate his several machines.

While I have described herein a mechanism 115 adapted to the binding of grain with cord alone, it is evident that with slight adaptation a wire-twisting device might be substituted for the knotting arrangement, and wire used as the binding material instead of cord.

The proper adjustment of the platform may be effected by means of the set-screw Z , which 120 clamps the suspending-bar to the rearwardly-extended beam of the main frame.

If desired, a small caster-wheel may be provided to assist in supporting the inner end of the platform at its rear side.

I claim as my invention—

1. In a grain-binder, the combination, with the main frame of the machine, of the rearwardly-extended bar C , the drag-bar D^2 , the platform carrying the raking mechanism, the sus-

- pending-bar D', connected to the platform at one end and slotted at the other end, and held by a bolt on the bar C, and a set-screw, Z, working on said bolt, whereby, through the adjustment of the bar D' and set-screw Z, the platform can be adjusted and held in the desired position, substantially as described.
2. In a grain-binder, the combination of the main driving-crank, the slotted pitman, and the raking mechanism driven thereby with the shaft G', having the foot-lever G² and the arm G, capable of being lifted into the path of the pitman, so as to disengage it from the crank, whereby the starting and stopping of the raking mechanism is placed under the control of the driver, substantially as described.
3. In a grain-binder, the combination of a reciprocating platform raking mechanism, and a binding mechanism operated directly by the said raking mechanism, substantially as described.
4. In a grain-binder, the combination, with a grain-platform, of a binding mechanism arranged at one end thereof, and a raking mechanism working within the platform, and mechanism for causing the raking mechanism to sweep the grain from the platform to the binding mechanism, and to afterward operate directly upon the binding mechanism to set the latter in motion, substantially as described.
5. In a grain-binder, the combination, with a binding mechanism, of a reciprocating rake adapted, in its forward movement, to gather the grain to the binding mechanism and to operate directly upon such mechanism to set it in motion to bind the gathered grain, and on its return or backward movement to reset the binding mechanism in readiness for a subsequent binding operation, and mechanism for reciprocating said rake, substantially as described.
6. In a grain-binder, the combination of the rake-frame and the bar connected thereto having the laterally-projecting pin with the angular slotted bar having the offset, the weighted pawl-arm, the connecting-bar, the shaft carrying the binding-arm, and the crank on the end of said shaft, substantially as described.
7. The combination of the stationary compressor-arm and the movable compressor pivoted thereto and having the laterally-projecting pin with the short slotted arm on the binding-arm shaft and the adjustable spring, substantially as described.
8. The combination, with the binding-arm having the lateral projection at its end, of the pivoted spring locking-catch for engaging with said projection to hold the arm locked when down, and the arm on the reciprocating rake-frame for operating said locking-catch, substantially as described.
9. The combination, with the clamping jaws on the binding-arm, of the centrally-pivoted bar operated by the reciprocating rake-frame and having the wedge-shaped projection for spreading apart said jaws to enable them to secure a tighter hold upon the cord, substantially as described.
10. The outer rotating tube or cylinder of the knotting device carrying the clamps or nippers, in combination with the non-rotating but longitudinally-sliding inner tube, having the projection for opening the jaws or nippers, substantially as described.
11. The combination of the outer rotating tube of the knotting device carrying the clamps or nippers, and the non-rotating but longitudinally-sliding inner tube having the projection for opening the jaws or nippers, with the longitudinally-sliding central hook and the sliding bar co-operating with said hook to grasp and hold the ends of the cord positively and pull them through the loop to form a hard knot, substantially as described.
12. The combination of the rotating outer cylinder or tube having the pinion on its rear end with the vibrating rack bar or segment, the bell-crank lever, and the intermediate connecting parts, and with the projection on the rake-frame for operating said bell-crank lever, substantially as described.
13. The combination of the outer rotating cylinder or tube carrying the clamps or nippers with the inner non-rotating tube and with the vibrating rack-bar having the cam on its rear side for retracting slightly the inner tube, substantially as described, for the purpose specified.
14. The combination of the inner tube having the downwardly-projecting arm at its rear with the detent for normally locking said arm and the pin on the reciprocating rake-frame for operating said detent to release said arm, substantially as described.
15. The combination of the sliding central hook-bar having the curved and bifurcated rear end with the spring-arm connected to said end and the projection on the reciprocating rake-frame for operating said spring-arm, substantially as described.

JACOB W. WILSON.
